(57) **CLAIM**

The ornamental design for a table with receptacle, as shown and described.

DESCRIPTION

FIG. 1 is a top plan view of a table with receptacle with cover in place showing our new design.

FIG. 2 is a side elevational view thereof.

FIG. 3 is a bottom plan view thereof.

FIG. 4 is front exploded perspective view of our table with a receptacle of our design shown in FIG. 2.

FIG. 5 is a front exploded perspective view of our table with a receptacle of our design shown in FIG. 2.

FIG. 6 is a top plan view of an alternate embodiment of our design.

FIG. 7 is a top plan view of a table with receptacle with a cover in place showing our new design.

FIG. 8 is a top plan view of an alternate embodiment of our design.

FIG. 9 is a front perspective view of the embodiment shown in FIG. 6.

FIG. 10 is a front perspective view of the design shown in FIG. 7; and,

FIG. 11 is a front perspective view of the embodiment shown in FIG. 8.
